OSCAR JUNGGREN, OF SCHENECTADY, NEW YORK, ASSIGNOR TO GENERAL ELECTRIC COMPANY, A CORPORATION OF NEW YORK.

GOVERNING MECHANISM FOR MIXED-PRESSURE TURBINES.

1,110,491.

Specification of Letters Patent. Patented Sept. 15, 1914.

Application filed September 5, 1912. Serial No. 718,673.

To all whom it may concern:

Be it known that I, OSCAR JUNGGREN, a citizen of the United States, residing at Schenectady, county of Schenectady, State of New York, have invented new and useful Improvements in Governing Mechanism for Mixed-Pressure Turbines, of which the following is a specification.

This invention relates to elastic fluid turbines, and especially to those arranged to be driven both by high pressure steam from a boiler plant and by low pressure steam exhausting from other high pressure engines or industrial apparatus. It is desirable to have the governing mechanism for such mixed pressure turbines as solid and substantial as possible in order to give good regulation and avoid difficulties in operation. In the present invention I have provided the following instrumentalities which in practice have worked out satisfactorily. The low pressure steam is controlled by a balanced valve operated by a hydraulic motor which is also connected to the high pressure valves of the turbine, so that in case there is insufficient low pressure steam the speed governor will operate the pilot valve of the motor and cause the latter to open the low pressure valve wider and in addition open the valves which admit high pressure steam to the machine.

There is also provided a safety device whereby upon an abnormal increase of speed of the machine, the valve will be detached from the operating mechanism and be permitted to close by its own weight, supplemented, if need be, by a spring. To prevent excessive slamming, a dash-pot is provided. There is also a lifting device to reconnect the valve to the governor mechanism after the emergency has passed. I also provide a pressure-responsive device which can act upon the hydraulic motor independently of the speed governor, and regulates the admission of steam in accordance with the pressure existing in advance of the balanced valve. This enables the machine to hold a constant load with variations in the steam pressure, and even if the low pressure steam should fail entirely.

In the accompanying drawing, Figure 1 shows one embodiment of my invention applied to a horizontal turbine of the Curtis type; Fig. 2 is a vertical section of the hydraulic governing mechanism, on a larger

scale; Fig. 3 is an elevation of a portion of Fig. 2, on a plane at right angles thereto; and Fig. 4 is a detail view of the safety catch and lifting device.

The horizontal turbine 1 is supplied with high pressure steam through the main 2, which is controlled by the throttle valve 3 provided with automatic closing mechanism 4 under control of the emergency governor 5. The admission of steam to the high pressure nozzles is controlled by valves which are operated by the cam shaft 6. Low pressure steam is supplied to said turbine by the main 7 in which is a balanced throttle valve 8 of the poppet type. This valve and also the cam shaft for the high pressure admission valves are operated by the hydraulic motor 9 whose pilot valve 9¹ in the chest 10 is connected to a floating lever 11 one end of which is connected by a link 12 to the arm 13 of the speed governor 14.

The piston rod 15 of the motor carries a rack 16 which meshes with a pinion 17 on the cam shaft 6. The said piston rod is in line with the stem 18 of the valve 8, to which it is detachably connected, preferably as follows:—A sleeve 19 is secured to said stem by a bolt 20, and carries (preferably on each side) a lug 21 with which engages a spring catch 22 pivoted on a block 23 secured to the lower end of the piston rod 15. Between the adjacent ends of the stem and the rod is a compression spring 24 preferably housed in a socket in the upper end of the stem 18. The lower portion 25 of the sleeve 19 is bell-shaped and fits over a head 26 on the bearing 27 through which the stem 18 passes; said bearing being arranged on the cap 28 of the valve casing 29, and containing a suitable packing device for the stem, such as the water-collecting grooves 30. The bell 25 and the head 26 form a dash-pot to prevent the valve from slamming, and the effectiveness of said dash-pot can be regulated by the pet cock 31, which affords a vent for the confined air.

In order to enable the emergency governor to trip the catch 22 at any point in its path as the valve moves up and down, a bar 32 is arranged parallel with said path of movement and adjacent to the tail of the catch. This bar is mounted on parallel links 33 so that it has a parallel-ruler motion. A crank arm 34 on the pivot of one of said links is connected by a rod 35 with the tripping 110

mechanism of the emergency governor 5. When the governor operates, it thrusts said bar toward the piston rod and disengages the catch 22 from the lug or lugs 21, no matter what the position of the valve may be. The weight of said valve and the thrust of the spring 24 at once shut the valve. To lift the valve so that the catch may again engage its lug or lugs, I provide a lever handle 33

10 attached to a pair of cams 37 which underlie the studs 38 projecting from the sides of the sleeve 19. By pulling down on the lever, the cams will raise the valve and its stem until the lugs snap into engagement with the catch.

To enable the turbine to carry a constant load irrespective of pressure variations, I connect with the valve casing 29, in advance of the valve, a casing 39 containing a flexible diaphragm which responds to changes in the pressure of the low-pressure steam. This diaphragm is connected to a lever 40 and exerts its upward pressure against the tension of a compression spring 41 arranged 20 under the other end of said lever. A rod 42 pivoted to this end is attached to an auxiliary floating lever 43 pivoted at one end to the floating lever 11 and at the other to a link 44 attached to a bracket 45 on the rack 25 16. Variations of pressure cause the diaphragm to force the lever 43 up or down, as the case may be, and thus raise or lower the pilot valve 9' and effect a corresponding shift in the rack and the valve 8; an increase 30 in pressure tending to close the valve, or vice versa. The connection of the lever 43 to the rack 16 produces a "follow-up" effect which prevents the valve 8 from moving too far at any given change in steam 35 pressure.

In accordance with the provisions of the patent statutes, I have described the principle of operation of my invention, together with the apparatus which I now consider to 45 represent the best embodiment thereof; but I desire to have it understood that the apparatus shown is only illustrative, and that the invention can be carried out by other means.

50 What I claim as new and desire to secure by Letters Patent of the United States, is:

1. In combination, a valve biased to closed position controlling a supply of motive fluid to a prime mover, a member for 55 operating said valve, a governor for said member, a latching device connecting the member to the valve stem, said latching device moving with the member and stem in response to the governor, means adapted to 60 be moved into engagement with and to operate upon said latching device to release the same in any position thereof, and an emergency governor for moving said means.

2. The combination with a valve control- 65 ling a supply of motive fluid to a prime

mover, a motor for operating said valve and a governor controlling the motor, said motor and said valve being detachably connected and the valve tending to close when the connection is released, of a member parallel to 70 the path of movement of said detachable connection, and an emergency governor for actuating said member to release the connection.

3. The combination of a valve controlling a supply of motive fluid to a prime mover, a motor for operating said valve having its piston rod in line with the valve stem, the piston rod and the valve stem being detachably connected and the valve 80 tending to close when the connection is released, a governor controlling said motor, means for releasing the detachable connection, and emergency governing means for actuating said means to cause said connection to be released.

4. In a mixed pressure turbine, the combination with a balanced low pressure valve, of an operating motor having a piston rod in line with the stem of said valve, a spring 90 catch connecting said rod and stem, a bar parallel to the path of movement of said catch, an emergency governor for actuating said bar to detach said catch, and a dash-pot for checking the drop of the valve. 95

5. In a mixed pressure turbine, the combination with a balanced low-pressure valve, of an operating motor having a piston rod in line with the stem of said valve, a sleeve secured to said stem and provided with one 100 or more lugs, a spring catch on the rod co-operating with said lugs, an emergency governor, a bar having a parallel-ruler motion connected to said governor and adapted to trip said catch, a bell-shaped portion on said 105 sleeve, and a head on the valve casing co-operating therewith to form a dash-pot.

6. In a mixed pressure turbine, the combination with a balanced low pressure valve, of a stem therefor having a socket in its 110 upper end, an operating motor having its rod in line with said stem, a spring in said socket abutting against the lower end of said rod, a detachable connection between said rod and stem, and an emergency governor adapted to trip said connection. 115

7. In a mixed pressure turbine, the combination with a balanced low pressure valve, of an operating motor therefor, a sleeve on the stem of said valve provided with laterally projecting studs, detachable connections between said sleeve and said motor, means for automatically tripping said connections, and lifting cams co-operating with said studs to restore said connections. 120 125

8. In a mixed pressure turbine, the combination with the high pressure valves, and the low pressure valve, of a motor for operating both, said motor being detachably connected with one of said valves, a pilot 130

- valve for said motor, a floating lever connected to said valve, a speed governor connected to said lever and an auxiliary floating lever also pivoted thereto and to the 5 piston rod of said motor, a device responsive to the pressure of the low pressure steam connected to said auxiliary floating lever, and means for releasing the detachable connection.
10. 9. In a mixed pressure turbine, the combination with the high pressure valves and the low pressure valve, of a motor for operating both, a pilot valve for said motor, a floating lever connected to said pilot valve, a speed governor controlling said pilot valve, an auxiliary floating lever pivoted to the other and pivotally connected to the piston rod of the motor, a diaphragm responsive to the low pressure steam, a lever 20 actuated by said diaphragm, a spring opposing the pressure on said diaphragm, and a rod connecting said lever with the auxiliary floating lever.
10. The combination of a valve controlling 25 a supply of motive fluid to a prime mover, a motor for operating said valve hav-

ing its piston-rod in line with the stem thereof, there being a rack carried by said piston-rod, a shaft having thereon means for actuating valve means controlling another 30 supply of motive fluid to said prime mover, and a pinion on said shaft in engagement with said rack.

11. The combination of a turbine having a plurality of supplies of motive fluid, valve 35 means for controlling each of said supplies, a motor for operating both said valve means, a speed governor for controlling said motor, there being a detachable connection between said motor and the valve means controlling one of said supplies, additional valve means for controlling the other of said supplies, and emergency governing means for said turbine for releasing said detachable connection and causing the closure 40 of said additional valve means.

In witness whereof, I have hereunto set my hand this 4th day of September, 1912.

OSCAR JUNGGREN.

Witnesses:

BENJAMIN B. HULL,
HELEN ORFORD.

It is hereby certified that in Letters Patent No. 1,110,491, granted September 15, 1914, upon the application of Oscar Junggren, of Schenectady, New York, for an improvement in "Governing Mechanism for Mixed-Pressure Turbines," an error appears in the printed specification requiring correction as follows: Page 1, line 40, for the word "governor" read *governing*; and that the said Letters Patent should be with this correction therein that the same may conform to the record of the case in the Patent Office.

Signed and sealed this 20th day of October, A. D., 1914.
